(57) **CLAIM**

The ornamental design for a six-hole half cylinder clamp, as shown and described.

DESCRIPTION

FIG. 1 is a perspective view of a six-hole half cylinder clamp showing my new design;

FIG. 2 is a left-side view thereof;

FIG. 3 is a right-side view thereof;

FIG. 4 is front view thereof;

FIG. 5 is a rear view thereof;

FIG. 6 is a top view thereof; and,

FIG. 7 is a bottom view thereof.

The broken lines illustrate portions of the six-hole half cylinder clamp that form no part of the claimed design.
